(57) **CLAIM**

The ornamental design for an integrated multi-purpose perception housing, as shown and described.

DESCRIPTION

FIG. 1 shows a front isometric view of an integrated multi-purpose perception housing.

FIG. 2 is a front isometric view thereof, showing top panels removed for ease of illustration.

FIG. 3 is an exploded front view of FIG. 1.

FIG. 4 is a right-side view of FIG. 1.

FIG. 5 is a front view of FIG. 1.

FIG. 6 is a bottom view of FIG. 1.

FIG. 7 is a rear view of FIG. 1;

FIG. 8 is an enlarged isometric view of a right side portion and a left side portion of the integrated multi-purpose perception housing; the center portion of the integrated multi-purpose perception housing shown in FIG. 2 has been removed for ease of illustration; and,

FIG. 9 is an enlarged view of the integrated multi-purpose perception housing taken from indication circle 9 of FIG. 5. The broken lines in the drawings illustrate portions of the integrated multi-purpose perception housing and form no part of the claimed design. The dot-dot-dash broken lines in the drawings illustrate boundaries of an enlargement that form no part of the claimed design.
